WARP TENSIONING BAR FOR KNITTING MACHINES

Carlos A. Hepp, Englewood, N. J., assignor to
Alfred Hofmann & Co., West New York, N. J.,
a corporation

Application August 14, 1951, Serial No. 241,833

7 Claims. (Cl. 66—146)

1

This invention relates to tension bars for warp knitting machines.

In warp knitting machines known in the art, tension bars are provided which guide the yarns from the warp reels to the knitting elements of the machine, such bars including resilient means for tensioning the advancing yarns during the knitting cycle. Such tension bars have excessive up and down motion, particularly in machines operating at high speeds. Such excessive motion adversely affects the quality of the knitted fabric and also impairs the efficiency of operation of braking and reel driving mechanisms which are commonly actuated by suitable connection to the tension bars.

Accordingly, an object of this invention is to provide improved yarn tension and guide means which has materially reduced motion during the several phases of the knitting cycle.

Another object of this invention is to provide a device of the character described which includes improved means variably adjusting the operation of the yarn tension means along the several sections of the yarn tension bar.

Other objects will in part be obvious and in part hereinafter pointed out.

The invention accordingly consists in the combination of elements and the arrangement of parts as exemplified in the embodiments herein-after shown and described.

In the drawing:

Fig. 1 is a side elevational view of a warp tension bar embodying the invention;

Fig. 2 is a top plan view thereof; and

Fig. 3 is a side elevational view of a modified form of the invention.

Referring in detail to the drawing and particularly to Fig. 1, 10 designates an improved warp guide and tension bar for a warp knitting machine. The same comprises a support 11 suitably mounted on the frame of the knitting machine and may be arranged for rocking motion about the longitudinal axis thereof. Extending at right angles from said support, are a plurality of similar, spaced arm members 12 which may be formed of light metal in inverted channel form. The inner end of each arm may be secured to the support by means of a screw 13.

The outer end of each arm member is formed with an angularly related bearing portion 14 in which is slidably mounted a pin 15 to provide for movement thereof substantially transversely of the arm member. The pin 15 is provided with a transverse projection 17 at the lower end thereof which is adapted to engage the lower end of bear-

ing portion 14 to limit the upward movement of the pin.

As shown in Fig. 2, the upper ends of pins 15 are interconnected by a longitudinally extending yarn guide bar 18 which is parallel to support 11. The bar 18 may be of a light and somewhat flexible material such as metal or the like.

Means is provided for resilient movement of the guide bar 18 relative to the arm members 12. To this end, a coil compression spring 19 is mounted on each pin 15, being located between the underside of the bar 18 and the upper end of bearing portion 14, thus biasing the guide bar to an upper position.

15 The arm members 12 may be resiliently supported by spring means generally indicated at 20 and more fully described in Patent 2,521,218. The springs 19 yield more readily than spring means 20, thus allowing the guide bar 18 to have resilient movement relative to arm members 12.

It will be apparent, that with a sheet of yarns *y* indicated by the dot and dash line, moving in the indicated path from the reels, not shown and directed by the bar 18, to the knitting elements, not shown, that any change in the tension of the yarns will cause pins 15 to move up or down through the action of the compression springs 19. With an increase in yarn tension, the springs will be compressed while a decrease in tension will cause the springs to expand, thus maintaining a uniform tension on the moving yarns. It is understood that springs 19 may be selected to provide suitable tensioning values. The angular relation of bearing portion 14 to the arm members 12 may be suitably determined to provide proper flow of the yarns.

40 The resilient capacity of the individual springs 19 may be separately controlled, as shown in Fig. 3. Here, the pins 15a are of extended length so as to provide a portion 21 extending below bearing portion 14. The lower end of portion 21 is threaded to receive a nut 22 which bears against a collar 23 on the pin portion. A second compression spring 24 is mounted on pin portion 21 between the collar 23 and the lower end of bearing portion 14.

45 It will be apparent that the spring action of each pin 15a may be regulated by adjusting the nut 22, thus determining the initial compression of springs 19. Since the guide bar 18 is somewhat flexible, variable tension responses may be provided along the length thereof, by individually adjusting the springs on the pins 15a. Thus, the quality of the knitted fabric may be accurately controlled and the selvage ends of the machine

may have differential tension for the yarns at the selvage portions of the knitted fabric.

In the event that the tension of the yarns moving over bar 18 exceeds the compression limits of springs 19, then arms 12 will move downwardly against the action of spring means 20, to rock support 11. The support 11 is adapted to be connected to suitable mechanism for braking or driving the reels, as more fully described in Patent 2,521,218.

It will be apparent that the excessive up and down movement of arm members 12 will be avoided, since the major portion of the yarn tensioning will be provided by the spring pressed pins 15 or 15a.

As various possible embodiments might be made of the above described invention, and as various changes might be made in the embodiments set forth, it is understood that all matter herein set forth or shown in the drawing, is to be interpreted as illustrative and not in a limiting sense.

Having thus described my invention, I claim as new and desire to protect by Letters Patent:

1. In a warp knitting machine, a support, an arm fixed to said support, a member mounted on said arm for slidable movement substantially transversely of said arm, a yarn tension bar mounted on said member and resilient means on said member for resiliently supporting said bar relative to said arm.

2. In a warp knitting machine, a support, an arm on said support, said arm including a bearing portion, a member slidably mounted in said bearing portion, a yarn tension bar mounted on said member and a compression spring on said member and located between said bar and said bearing portion.

3. In a warp knitting machine, a support, an arm extending from said support, a pin slidably mounted on said arm, yarn tension means mounted on said pin and spring means for resiliently controlling the movement of said pin.

4. In a warp knitting machine, a support, an

5 4 arm extending from said support, said arm including an angular bearing portion, a pin slidably mounted in said bearing portion, yarn tension means mounted on said pin and resilient means for urging said yarn tension means in a given direction.

10 5. In a warp knitting machine, a movable support resilient means for controlling the movement of said support, a yarn tension bar movably mounted on said support, second resilient means for controlling the movement of said tension bar relative to said support, said second resilient means having a greater yieldability than said first resilient means.

15 6. In a warp knitting machine, a support, an arm extending from said support and including a bearing portion, a pin slidably mounted in said bearing portion, yarn tension means including a bar mounted at one end of said pin, spring means on said pin for urging said bar in a given direction and second spring means on said pin for controlling the operation of said first mentioned spring means.

20 7. In a warp knitting machine, a flexible yarn guide bar, a support, a plurality of spaced members for mounting said bar on said support, the outer end of each member including a bearing portion, a pin slidably mounted in each bearing portion, one end of each pin engaging said bar, resilient means on each pin for urging said bar in a given direction and means for independently adjusting the action of each resilient means.

CARLOS A. HEPP.
